UNITED STATES PATENT OFFICE.

RICHARD H. WELLES, OF KENOSHA, WISCONSIN, ASSIGNOR TO THE BADGER BRASS MFG. CO., OF KENOSHA, WISCONSIN, A CORPORATION OF WISCONSIN.

HEADLIGHT.

1,015,750.

Specification of Letters Patent.

Patented Jan. 23, 1912.

Application filed May 3, 1909. Serial No. 493,460.

To all whom it may concern:

Be it known that I, RICHARD H. WELLES, a citizen of the United States, residing at the city of Kenosha, county of Kenosha, and State of Wisconsin, have invented certain new and useful Improvements in Headlights, of which the following is a specification.

This invention relates to improvements in headlights and refers more specifically to improvements in headlights of that type which are employed for lighting the roadway in advance of vehicles, boats, etc., the particular embodiment shown being suitable for use in connection with automobiles.

Among the salient objects of the invention are to provide a construction in which the parallel ray beam may be temporarily eliminated or dispersed; to provide a construction in which the direction of the normal light of the lamp may be so changed as to eliminate or modify the glare due to the parallel or approximately parallel rays; to provide a beam of parallel or approximately parallel rays; to provide a construction in which the above objects may be accomplished by simply shifting the nozzle or burner out of the normal focus of the lamp; to provide a construction in which the burners of two or more headlights may be simultaneously shifted into or out of focus at will to accomplish the purpose referred to; to provide a simple, inexpensive and effective construction which can be readily affixed to any well known type of lamp or headlight; and in general to provide an improved construction of the character referred to.

The invention consists in the matters hereinafter described and more particularly pointed out in the appended claims.

In the drawings Figure 1 is a vertical axial sectional view of a headlight equipped with my invention. Fig. 2 is a fragmentary vertical sectional view taken approximately at right angles to the view shown in Fig. 1. Fig. 3 is a perspective view of the front end of an automobile showing two headlights in place thereon equipped with my invention.

In headlights as now commonly organized for use in connection with automobiles, locomotives, boats, etc., the light is so reflected as to form a parallel ray beam. When an automobile is approaching an object, it is 55 desirable to modify or lessen the glare of the light from the headlights by dispersing or changing the direction of the beam. I accomplish this by temporarily shifting the burner out of the normal focus of the lamp. 60

Referring to the drawings, 1 designates as a whole the headlight casing which is shown as consisting of a cylindric side wall member 2, a flaring front rim 3 and an outwardly convex rear end wall 4. Seated in the rear end of the casing is a reflector 5 of that type known as Mangan mirror; this reflector being of well known construction and serving to not only reflect the rays but to modify their direction so that the rays emanating from the focal point of the lamp are reflected and at the same time brought into parallelism with each other. For the protection of the interior parts of the headlight the front end of the casing is closed by a 75 plain glass or crystal 6, which, as shown, is made of uniform thickness throughout and therefore does not substantially vary the direction of the rays passing therethrough.

7 designates the nozzle or burner which 80 as usual enters through an aperture 11 formed in the lower side of the headlight casing, rises vertically therein, and terminates in a burner tip 7^a located just below a focal point of a headlight, so that the burning jet will occupy this focal position. The burner in this instance is an acetylene gas burner and a gas supply pipe or tube is connected with the capital 30 of the nozzle at the lower end of the latter in a well 90 known manner. The nozzle is so mounted that it may be shifted above the focal point of the lamp. To this end a centrally apertured block 8 is soldered or otherwise secured to the lower side of the casing and is 95 internally screw threaded, as shown at 9 to receive and hold a tubular socket member or burner housing 10 through which the nozzle extends. The aperture 11 in the casing is of slightly less diameter than the corre- 100

sponding aperture in the block 8, thus forming an annular shoulder 12. The lower part of the nozzle 7 terminates in an enlarged extension 13 forming a shoulder 14, and between this shoulder and the shoulder 12 upon the casing is interposed the coiled extension spring 15 which tends to force the nozzle downwardly into its normal position shown in full lines in Fig. 1. The downward movement of the nozzle is positively limited by means of a collar 7' secured to the former by a screw 7".

In order to force the nozzle or burner upwardly out of focus of the lamp, a bell crank 16 is pivotally connected at 17 to a bracket 18 riveted as shown at 19 to the lower side of the casing. One arm 20 of this crank is forked as shown more clearly in Fig. 1, and each end of the fork is provided with a closed slot 23 adapted to engage the pin 22 extending through either side of the nozzle 7.

In the present instance I have shown two headlights equipped with my invention and mounted at the front of the hood of an automobile in the usual manner. The cranks 16 are interconnected to operate synchronously. Accordingly to the lower arm 24 of each crank is fastened an operating cord 25 which extends across the front of the hood and is trained around a sheave 26 mounted upon the bracket 27 which supports the headlight. The rear end of the cord is then carried back to the driver in any suitable manner. It will be thus seen that the nozzles may be simultaneously shifted out of focus by simply operating the cord 24, and without necessitating the stopping of the machine. When the cord is released the nozzles will automatically spring back into normal position through the action of the coiled springs 15.

It is apparent from the foregoing that the invention may be used with various kinds of lamps, and that the details of construction may be more or less modified without departing from the spirit of the invention.

I claim as my invention:

50 1. In a lamp of the headlight type, the combination with a headlight casing, of a reflector seated therein, a burner mounted in the casing, self restoring mechanism movably and yieldably supporting said burner 55 in its normal position, means for effecting a bodily shifting of the burner out of its normal position but within the ray field of said reflector, and operative connections extending from said shifting means to a distance 60 from the lamp.

2. In a lamp of the headlight type, the combination with a headlight casing, of a reflector seated therein, a burner mounted in the casing for axial or endwise movement, a 65 spring arranged to hold said burner yield-

ably in its normal position, operative mechanism for effecting a sudden bodily displacement of the burner against the action of said spring, said operative mechanism extending to a point remote from the lamp.

70 3. In a lamp, the combination of a casing, a reflector and a burner-housing each mounted in said casing, a burner mounted for endwise movement through said housing and having its tip normally positioned to 75 locate the source of light at the focus of said reflector, and means for effecting a temporary endwise displacement of said burner; said burner being constructed and arranged to automatically return the source of light 80 to the focus of said reflector; substantially as described.

4. In a lamp, the combination of a casing, a reflector and a burner-housing each mounted in said casing, a burner mounted 85 for endwise movement through said housing and having its tip normally positioned to locate the source of light at the focus of said reflector, means for effecting a temporary endwise displacement of said burner, and 90 means for automatically returning said source of light to the focus of said reflector; substantially as described.

5. In a lamp of the headlight type, the combination of a casing, a reflector and a 95 burner-housing each mounted in said casing, a burner mounted for endwise movement through said housing, a spring arranged to hold said burner yieldably and normally with the source of light at the focus of said 100 reflector, and means for effecting a temporary bodily displacement of said burner against the action of said spring; substantially as described.

6. In a lamp, the combination of a casing, 105 a reflector mounted within the casing, a member slidably mounted upon the casing to move in a substantially vertical direction, a burner tip carried by the said slidably mounted member and the flame of the 110 burner being at the focus of the reflector when the member is in normal position at the lower limit of its movement, and means for temporarily raising the slidably mounted member against the action of gravity to 115 throw the flame away from the focus of the reflector.

7. In a lamp, the combination of a casing, a reflector mounted within the casing, a tubular guide at the bottom of the casing, a 120 stem slidably mounted within the tubular guide, a burner tip carried by the stem and the flame of the burner tip being at the focus of the reflector when the stem is at the lower limit of its movement, and means for temporarily raising the stem against the action of gravity to throw the flame away from the focus of the reflector.

8. In a lamp, the combination of a casing, 125 a reflector arranged within the casing, a tu-

bular guide carried by the casing, a member slidably mounted within the tubular guide, a burner tip carried by the said member and normally being in such a position that the

5 flame is at the focus of the reflector, a lever connected to the slidably mounted member, and means coöoperating with the lever to

move the said slidably mounted member and throw the flame from the focus of the reflector.
